CLOTHESPIN

Louis R. Dold, Oakland, Calif.

Application April 19, 1949, Serial No. 2,130

Term of patent 14 years

(Cl. D17—6)

To all whom it may concern:

Be it known that I, Louis R. Dold, a citizen of the United States and a resident of Oakland, in the county of Alameda, State of California, have invented a new, original, and ornamental Design for a Clothespin, of which the following is a specification, reference being had to the accompanying drawings, forming part thereof, wherein

Figure 1 is a side face view of a clothespin embodying my new design.

Figure 2 is an edge view of the clothespin.

Figure 3 is an edge view of the clothespin taken from the opposite side than is the view of Figure 2.

Figure 4 is a bottom plan view of the end portion only.

I claim:

The ornamental design for a clothespin, substantially as shown.

LOUIS R. DOLD.
